UNITED STATES PATENT OFFICE.

JAMES E. SMITH, OF ST. LOUIS, MISSOURI.

SEESAW.

Application filed July 22, 1920. Serial No. 398,212.

To all whom it may concern:

Be it known that I, JAMES E. SMITH, a citizen of the United States, residing at the city of St. Louis, in the State of Missouri, 5 have invented certain new and useful Improvements in Seesaws, of which the following is a specification.

This invention is a simplified and improved seesaw and merry-go-round, and is 10 so constructed as to permit simultaneous rotary and seesawing motion. On account of the way in which it is built, it can be constructed more cheaply than many others.

In the accompanying drawings forming 15 part of this specification, in which like numbers of references denote like parts wherever they occur,

Figure 1 is a side elevation;

Figure 2 is a top plan view;

20 Figure 3 is an end elevation; and

Figure 4 is a perspective view of the lower part of the standard.

The base comprises a plurality of feet 1, a baseplate 2, and a standard 3. The top of 25 standard 3 is reduced and the said reduced part surrounded by ferrule 4. A pin 5 is socketed in the said reduced part.

Cleats 6 are formed on the bottom of standard 3 and overlap feet 1 and steady the 30 connection between the same.

Baseplate 2 and cleats 6 are nailed or otherwise secured to feet 1, there being a hole 7 in baseplate 2 for the passage of standard 3. Pin 5 is socketed in hole 8 in 35 the pivoted swinging member 9 mounted by means of rod or bolt 10 or other suitable means in arms 11, secured by screws 12 or other suitable means to plate or brace 13. Screws 12 pass through parts 14 arranged 40 at an angle to arms 11.

The brace 13 may either be formed integral with or attached to the beam 15, which comprises the central body part 16, and the forked ends 17 contain slots 18 which extend clear to the ends of the beam 15. 45 Tongues 19 are located in the said slots 18

and bear handle-bar uprights 20, which carry the handle-bars 21.

Seats 22 are attached by screws 23 or otherwise to tongues 19, and keeperplates 50 24 cross slots 18 so as to hold tongues 19 therein and seats 22 in place.

Cleats 25 brace the forked ends 17. Tongues or blocks 26 borne by cleats 25 are inserted in the forked ends 17. Seats 22 55 are provided with backs 27. Nuts 28 permit adjustment of seats 22 longitudinally in slots 18, being tightened to hold the seats 22 stationary after the tongues 19 have been moved to any desired position in slots 18. 60

Having thus described this invention, I hereby reserve the benefit of all changes in form, arrangement, order, or use of parts, as it is evident that many minor changes may be made therein without departing from 65 the spirit of this invention or the scope of the following claim:

I claim:

A seesaw comprising substantially flat wooden leg members arranged at angles of 70 ninety degrees relatively to one another, a wooden standard rising from said legs and provided with integral rigid depending pins engaging the angles between said legs, a base plate surrounding said standard and secured 75 to the upper faces of said legs, a reduced extension provided at the upper end of said standard, a collar surrounding said reduced extension to prevent spreading of the reduced extension, a socket provided in said 80 reduced extension, a depending pin rotatably mounted in said socket and having laterally extending arms, a horizontally disposed pivot pin passing through said arms, spaced angle irons having vertical portions 85 mounted on said pivot pin, a beam mounted on said angle irons, and seats and handle bars arranged at the ends of said beam.

In testimony whereof I hereunto affix my signature.

JAMES E. SMITH.
